UNITED STATES PATENT OFFICE.

RUDOLPH MUELLER, OF CHICAGO, ILLINOIS.

DESIGN FOR A CONTAINER FOR A LIQUID-DISPENSER.

59,672.

Specification for Design.

Patented Nov. 15, 1921.

Application filed January 20, 1921. Serial No. 438,748. Term of patent 7 years.

To all whom it may concern:

Be it known that I, RUDOLPH MUELLER, a citizen of the United States, residing at Chicago, in the county of Cook and State of Illinois, have invented a new, original, and ornamental Design for a Container for a Liquid-Dispenser, of which the following is a specification, reference being had to the accompanying drawing, forming a part thereof.

The figure is a side elevation of a container for a liquid dispenser showing my new design.

I claim:

The ornamental design for a container for a liquid dispenser, as shown.

RUDOLPH MUELLER.
